CLAIM

We claim the ornamental design for a hand-held electronic device cover, as shown and described.

DESCRIPTIONFIG. 1 is a front perspective view of a hand-held electronic device cover;
 FIG. 2 is a back perspective view of the hand-held electronic device cover;

FIG. 3 is a front elevation view thereof;

FIG. 4 is a back elevation view thereof;

FIG. 5 is a left elevation view thereof;

FIG. 6 is a right elevation view thereof;

FIG. 7 is a bottom plan view thereof; and,

FIG. 8 is a top plan view thereof.

In the drawings, the broken lines depict unclaimed environment.
